J. Taylor Webster, of New York, N.Y.

Assignor to

Edw. A. Harvey, of Brooklyn, N.Y.

Letters Patent No. 1993-Dated Oct 18, 1864.

Design for a Floor Oil Cloth.

The schedule referred to in these Letters Patent and making part of the same.

To all whom it may concern;

Be it known that J. Taylor Webster of the City, County and State of New York, have invented or produced a new and original design for a pattern to be printed on floor oil cloth, in colors similar to those painted on the drawings accompanying this specification or in other colors substituted in the place of those painted on the drawings herewith; and I do hereby declare that the drawings accompanying this specification do give and convey to any one skilled in the art of printing oil cloths a more defined and thorough description of the nature of my invention than it is in the power of language otherwise to convey and is sufficient to enable any one skilled in the art of printing oil cloths to use my invention.

What I claim as my invention and desire to secure by Letters Patent is -

The configuration of the design heretounto annexed when made by being printed on floor oil cloth in the form similar to the drawings accompa-
